US00D912274S

(12) **United States Design Patent** (10) Patent No.: **US D912,274 S**
(45) Date of Patent: **** Mar. 2, 2021**

(54) **COMBINATION DOORS AND HEADER**

- (71) Applicant: **Apple Inc.**, Cupertino, CA (US)
- (72) Inventors: **Jonathan P. Siegel**, San Francisco, CA (US); **Christopher M. Green**, Woodside, CA (US); **James Andrus**, San Francisco, CA (US); **David del Villar Fernandez**, San Francisco, CA (US); **David Nelson**, London (GB); **Stefan Behling**, London (GB); **David Summerfield**, London (GB); **James McGrath**, Cupertino, CA (US); **Ed Wright**, San Jose, CA (US); **Bo Yoon**, San Francisco, CA (US); **Ton Men Banh**, Santa Clara, CA (US)
- (73) Assignee: **Apple Inc.**, Cupertino, CA (US)
- (**) Term: **15 Years**
- (21) Appl. No.: **29/584,026**
- (22) Filed: **Nov. 10, 2016**

Related U.S. Application Data

- (63) Continuation of application No. 29/517,044, filed on Feb. 9, 2015, now Pat. No. Des. 771,836.

(57) **CLAIM**

The ornamental design for a combination doors and header, as shown and described.

DESCRIPTION

FIG. 1 is a front perspective view of a combination doors and header in a first state showing the claimed design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a front perspective view of the combination doors and header of FIG. 1 in a second state; FIG. 9 is a front view thereof; FIG. 10 is a rear view thereof; FIG. 11 is a left side view thereof; FIG. 12 is a right side view thereof; FIG. 13 is a top view thereof; and, FIG. 14 is a bottom view thereof.

The dashed broken lines in the figures show portions of the combination doors and header that form no part of the claimed design.

The dot-dash broken lines in the figures show boundaries that form no part of the claimed design.

1 Claim, 6 Drawing Sheets
